UNITED STATES PATENT OFFICE.

EUSTACE OXLEY, OF LYNN, MASSACHUSETTS, ASSIGNOR TO THE GENERAL ELECTRIC COMPANY, A CORPORATION OF NEW YORK.

MULTIRATE METERING.

SPECIFICATION forming part of Letters Patent No. 717,262, dated December 30, 1902.

Application filed July 27, 1899. Serial No. 725,230. (No model.)

To all whom it may concern:

Be it known that I, EUSTACE OXLEY, a subject of the Queen of Great Britain, residing at Lynn, in the county of Essex, State of Massachusetts, have invented certain new and useful Improvements in Multirate Metering, (Case No. 1,099,) of which the following is a specification.

The object of my invention is to permit a plurality of meters installed in consumers' plants or buildings and designed to register the consumption of current at different rates to be controlled from a central station, so as to determine at a convenient point the hours during which the consumer shall be given the benefit of a reduced charge.

In operating systems of current distribution and supply it is desirable to encourage the use of current during periods when the load is light, thereby tending to decrease the disparity in load between day and night service and conducing to a more efficient and profitable operation of the system. In order to provide for such service, it is the practice sometimes to install at a consumer's station two or more meters or recording devices having different recording rates, according to the amount of discount allowed for use of current during the periods of light load on the system or in some cases a single meter capable of registering at different rates. Various methods have been proposed for automatically controlling the connections of such meters, so as to obtain the desired rate at the proper time. Some of these depend for their operation upon apparatus located at the consumer's station and others are controlled directly from the central station or some other control-point easy of access to the employees of the supply company. My invention relates to the latter type of control. I have heretofore described in patents granted to me various systems for establishing such control from a single controlling-point. In prior systems described by me I have shown means for accomplishing similar results by means of a control wire or wires extending from the supply-station and switching apparatus at the consumers' stations controlled thereby.

In my present invention I accomplish the desired result by running an independent control-wire from a suitable point—say the

central station—and providing means for connecting the meter-operating circuits between said control-wire and the supply-wires of the system, so as to produce the desired rate of registration or throw in the desired meter, my present invention being characterized by the fact that no switching mechanism is employed at the consumers' stations and a single control-wire may be employed.

In the accompanying drawings, which illustrate my invention, I have shown in Figure 1 in diagram such a plan of control as applied to a three-wire distributing system, the potential of the shunt-circuit of the meter being the maximum potential of the system. In Fig. 2 I have shown a similar arrangement, the shunt meter-circuit being connected between an outside wire and the neutral wire, as is usual in meters of the so-called "high-efficiency" type. My invention is not, however, limited in application to three-wire systems, but may be employed generally with supply systems in which an independent control-wire is employed to determine any one of a plurality of registering rates by means controlled at a central station or other controlling-point.

Referring first to Fig. 1, 1 2 3 represent the three distributing-wires of a circuit, and 4 a control-wire extending throughout said circuit or desired portions thereof and provided at a controlling-point, as a central station, with means for directing registering current through either of a plurality of meters 5 6 5^a 6^a having separate dials. The specific means employed in the system illustrated consists of a switch 7, connected to the control-wire and adapted to throw it into communication with different supply-wires of the system, the several meters being connected, respectively, with these wires, so that by a change of the switch the operative circuits of the meter are opened or closed. The types of the meter shown in the drawings are provided with two circuits, one of which is in series with the work and the other in shunt. The shunt-circuits include a high-resistance armature, which, as shown, is of the well-known Thomson recording wattmeter type. The details of construction are well understood by engineers versed in the art, and are therefore omitted from the drawing, which

is intended merely to show diagrammatically a familiar type of meter. It will be seen that the shunt-circuit of meter 5 leads from the main 1 by way of a resistance and the armature-circuit directly to the control-wire 4, whereas the shunt-circuit of the more rapidly registering meter 6 passes from the main 3 through part of the field-magnet of meter 5, and thence by a resistance in the armature-circuit back to the control-wire. As the controlling-switch 7 at the central station is connected in the position shown in the drawings with the supply-pipe 3 the meter 5 is registering, whereas the meter 6 is cut out. The controlling-circuits of the meters are as follows: The shunt-circuit is completed by way of supply-wire 1, resistance 9 and armature, shunt connection 10 of the control-wire 4, and thence by way of the switch 7 at the controlling-station to wire 3. Thus the maximum potential of the mains is on the shunt-circuit. The shunt-circuit of meter 6 being connected with wire 3 and the control-wire being similarly connected with said wire in the position of switch 7, as shown in the drawings, there is no difference of potential between its terminals and it remains inactive. The work-circuit for the meter 5 is from conductor 1 by way of connection 11 through the field-coils of both meters and back to supply-wire 3 by way of connection 12. By throwing the switch 7 to the open contact 13 at the controlling-station the control-wire will be connected with outside wire 1, thereby giving it the same potential as said wire, and a difference of potential will be imposed at the terminals of the shunt-circuit of meter 6, whereas the same potential will be imposed on the terminals of meter 5, which connect, respectively, with the outside wire 1 and with the control-wire 4.

In the modification shown in Fig. 2 the same system of control is embodied, except that the meter-shunts are so arranged that either meter may be coupled by means of the control-wire between the middle wire and one of the outside wires of the supply system.

The meters may be constructed primarily in any suitable manner to give them different registering rates. In the position of the switch shown in the diagram the meter 6 is registering. As will be seen, its shunt-circuit terminals connect, respectively, with the control-wire 4 and with one of the outside mains 3, thereby producing a difference of potential, which sends an operating-current through the armature. The meter 6^a, however, has its shunt-terminals connected with the control-wire 4 and with the neutral wire 2. As the latter is in metallic connection with the control-wire through the switch-arm in the position illustrated, both sides of the shunt are at zero potential and no operating-current flows through the meter. If, however, the switch be thrown to the open contact, the meter 6 will be cut out, while an operating-current will flow through the shunt-

circuit of the meter 6^a by way of control-wire 4, which is raised to the potential of supply-wire 3 by the change of switch connections, and thence through the shunt to the neutral wire 2. Thus it will be seen that the change of position of the switch shifts a supply-wire out of connection with one meter into connection with the other.

My invention is not limited in application to independent meters for establishing the different registering rates. A single registering-train may be employed and the rate determined by a variable resistance according to a known type of construction, in which case, of course, the different positions of the control-switch simply determine the cutting in and out of the resistance, the terminals of which connect with the different potential mains.

What I claim as new, and desire to secure by Letters Patent of the United States, is—

1. A multirate-meter system comprising a distributing-circuit, a single control-wire, meter-operating circuits having one terminal of the rate-determining circuit of the several meters connected respectively to wires of different potential and the other to the control-wire by continuously completed electric paths, and a switch at a control-station for changing the potential character of the control-wire.

2. A multirate-meter system comprising a distribution-circuit, a single control-wire, multirate-meter apparatus at the several stations having an operating-circuit in continuous electric connection with the distribution-circuit and the control-wire, and a switch at the control-station for imposing operating-potential on a metering apparatus of desired rate.

3. A multirate-meter system comprising a three-wire distribution-circuit, a single control-wire, multirate-meter apparatus at the several stations having the several rate-determining circuits connecting respectively at one end with different distribution-wires and at the other end with the control-wire, said connections being continuously completed, and a switch at the control-station for altering the potential character of the control-wire.

4. A multirate-meter system comprising a three-wire distribution-circuit, a single control-wire, multirate-meter apparatus at the several stations having an operating-circuit provided with continuous fixed connections between wires of different sign and a control-wire, and a switch at the central station for connecting the control-wire with wires of different sign.

In witness whereof I have hereunto set my hand this 24th day of July, 1899.

EUSTACE OXLEY.
